SWIVEL-CHAIR BASE OR SIMILAR ARTICLE

Joseph Burger, Brooklyn, N. Y.

Application July 19, 1957, Serial No. 47,008

Term of patent 3½ years

(Cl. D15—1)

I claim:

The ornamental design for a swivel-chair base or similar article, as shown.
